UNITED STATES PATENT OFFICE.

JEAN ALEXANDRE REY, OF PARIS, FRANCE.

MECHANISM FOR CONTROLLING MOVEMENT

1,299,509.

Specification of Letters Patent.

Patented Apr. 8, 1919.

Application filed November 30, 1914. Serial No. 874,937.

To all whom it may concern:

Be it known that I, JEAN ALEXANDRE REY, of 26 Avenue de Suffren, Paris, France, engineer, have invented a new and useful Improvement in Mechanism for Controlling Movement, which improvement is fully set forth in the following specification.

This invention has for its object improvements in mechanism for controlling movement at a distance, such improvements being particularly applicable to mechanism for the central control of guns on board ship.

For this purpose it is necessary to be able to simultaneously and continuously (or permanently) aim several guns from a single control station where the fire director is. The guns should therefore always remain parallel with each other and with the controlling member.

Nevertheless in practice it is necessary to provide for a case in which the guns deviate from the position which they should be in. This may take place after firing by reason of the great strains thereby produced, or this may take place owing to some abnormal resistance, or to damage, or to the momentary movement of one gun only.

In this case so soon as the cause of the abnormal deviation has disappeared, the gun should return of itself to the normal position.

According to this invention I combine together two controls of known type operated from a single control station (an aiming telescope for example) and actuating one or more controlled members (guns and search light for example) through the intermediary of differential gearing or its equivalent. One control is rapid (but may be occasionally faulty because of a certain angular separation between the control member and the controlled member or members) and mainly actuates the controlled member or members, while the other control, which is accurate for such angular separation, makes the corrections and acts to correct the deviation which may take place between the control member and the controlled member or members, the two controls acting simultaneously.

The second control should respond for a deviation less than that required for the precision agreed upon.

The invention is illustrated in the accom-

panying drawings as applied to aiming guns, wherein—

Figure 1 is a diagrammatic view illustrating one arrangement embodying the invention, and

Fig. 2 is a diagrammatic view illustrating a modified arrangement embodying the invention.

a is a usual aiming telescope mounted on an aiming apparatus or bridge *b*; *c* represents a support for the bridge with which support guns such as *d* should be maintained parallel.

One gun *d* only is shown, but the circuits are indicated to show that any number of guns may be controlled simultaneously.

In Fig. 1 is shown an arrangement for aiming a gun with respect to altitude. A small dynamo electric machine *e* is employed to rotate the central controlling element, such as a telescope *a*, through the intermediary of the worm 1, sector 2, support *c* and bridge *b*. A second dynamo electric machine *e*₁ is connected in parallel with the motor *e* and actuates the controlled element, such as a gun *d*, through the intermediary of differential gearing *f* to be described hereinafter, it being understood that there is a separate motor *e*₁ for each of the controlled elements. The motor *e*₁ constitutes the main actuating means for the gun *d* and may cause the gun to be rotated in either direction and at the required speed, simultaneously with a corresponding movement of the telescope, through manipulation of a reversing control or switch-lever *g* in the circuits of the two motors *e* and *e*₁. This lever is positioned to be operated by the fire director when stationed at the telescope *a*. As illustrated, the system controlled by the lever *g* is of the potentiometer type which admits of the obtaining of the speed desired.

As motors *e* and *e*₁ are connected in parallel, actuation of the control-lever *g* starts both motors in the same direction and at the same speed. These motors are synchronized by any desired mechanism, that illustrated comprising three rings *h* mounted upon each of the respective motor shafts and engaged by brushes connected in parallel. Thereby each of the motors constitutes a generator of alternating current of similar phase, and as these generators are

connected in parallel, substantially synchronous movement of the motors is insured.

The secondary actuating means for each gun d comprises a direct-current motor e'_1 , mounted adjacent the motor e_1 . Motor e'_1 is automatically actuated to rotate in either direction and at a suitable speed by a controlling mechanism which is operated as soon as the gun d deviates from its normal or predetermined relation with the support c by an amount greater than that necessary for the required precision. This motor e'_1 is connected with the differential by which motor e_1 moves the gun d . The arrangement illustrated and preferred, though various other arrangements will suggest themselves to those skilled in the art, comprises worms 3 and 4 upon the shafts of motors e_1 and e'_1 , these worms respectively meshing with worm-wheels 5 and 6 upon the shafts of bevels 7 and 8. Bevels 7 and 8 mesh respectively with bevels 9 and 10 journaled on gear 11, and constitute a differential. Gear 11, through pinion 12, worm 13 and sector 14, moves the gun d to the desired angular amount. Normally, motor e'_1 is stationary and thereby holds bevel 8 stationary. The rotation of the bevel 7 by motor e_1 then produces a rotation of gear 11 about its axis whereby the gun d is moved. If motor e'_1 is actuated, it causes a rotation of bevel 8 which, depending upon the direction of rotation, will vary the speed of rotation of gear 11, correcting the movement imparted to the gun d by motor e_1 .

While various means may be employed to automatically actuate the motor e'_1 , when gun d and telescope a lose their normal or predetermined relationship, such as parallelism, that preferred comprises an apparatus of known construction employing the principle of the Wheatstone-bridge and only shown conventionally on the drawing. Mounted to move respectively with the support c and the gun d are movable contact members 15 and 16 which sweep over graded resistances mounted in the boxes i and i' . So long as the contact members 15 and 16 move corresponding amounts, the variation in the resistance of the respective arms of the circuit is equal and no current flows through the bridge circuit. So soon, however, as contact members 15 and 16 move disproportionate amounts there is a corresponding difference in the resistance in the two arms of the circuit, whereby there is a difference of potential between the boxes i and i' , and a corresponding flow of current through the bridge circuit. This flow of current through the bridge circuit may be utilized in any preferred way to start motor e'_1 in the appropriate direction for correcting the movement of the gun d . The preferred arrangement comprises relays (not shown) actuated by the current flowing

through the bridge circuit, these relays closing switches in the circuit of the motor e'_1 to start the same in either forward or reverse direction as the case may be. As soon as motor e'_1 has caused a correction of the deviation of the gun d and restored it to parallelism with the support c , the balance of the electrical system controlled by the contact members 15 and 16 is restored, no current flows through the bridge circuit, and the relays are restored to normal position and motor e'_1 again held stationary.

The motor e'_1 comes into action in the following cases:

1. When speed is very low, the voltage at the brushes of the motors e, e'_1 is no longer sufficient to insure their synchronism.
2. When the gun has deviated for any reason.
3. When the telescope has deviated for any reason.
4. When the back lash of the gearing between the motor e'_1 and the gun d exceeds the required precision.
5. When an accident or abnormal resistance renders the motor e'_1 stationary.

The training of the gun is effected on the same principle by other similar parts.

In place of continuous current motors provided with three rings any other type of synchronous motor may be employed.

In place of the differential gearing any other equivalent arrangement may be employed.

Fig. 2 shows a modification applied to the training of guns, this modification differing from that heretofore described in that motor e_1 directly rotates a table j through the worm 17, worm-gear 18, worm 19, and teeth upon the table j . Table j carries a direct-current motor k and a gun d , the latter being mounted upon an auxiliary table 20 which may be rotated by the motor k through the intermediary of the worm and worm-gear 21. The means for starting and stopping the motor k is the same as that heretofore described with respect to the modification of Fig. 1. So long as motor e_1 moves gun d in parallelism with support c , motor k will be stationary and the auxiliary table 20 will be held by motor k stationary with respect to table j . Upon a deviation from the aforesaid parallelism, motor k will rotate in the appropriate direction to rotate auxiliary table 20 and gun d to an amount to rectify the deviation.

Claims:

1. In a mechanism for controlling movement at a distance, the combination with two or more movable elements normally moving in a predetermined relation and synchronized motors for moving the same, of means for correcting deviations from said predetermined relation comprising an auxiliary motor geared to one of said elements and electrical

devices under the control of said elements for starting and stopping said auxiliary motor upon the occurrence and correction respectively of a deviation.

5 2. In a mechanism for controlling movement at a distance, the combination with two or more movable elements normally moving in a predetermined relation and synchronized motors for moving the same, of means for correcting deviations from said predetermined relation comprising a differential connected at one side to one of said motors, an auxiliary motor connected to the opposite side of said differential, connections between said differential and the corresponding said element, and electrical devices under the control of said elements for starting and stopping said auxiliary motor upon the occurrence and correction respectively of a deviation.

0 3. In a mechanism for controlling movement at a distance, the combination with two or more movable elements normally moving in a predetermined relation and synchronized motors for moving the same, of means for correcting deviations from said predetermined relation comprising an auxiliary motor geared to one of said elements, and Wheatstone bridge apparatus operatively connected with said auxiliary motor for starting 30 and stopping the same.

4. In a mechanism for controlling movement at a distance, the combination with two or more movable elements normally moving in a predetermined relation and synchronized motors for moving the same, of means for correcting deviations from said predetermined relation comprising an auxiliary motor geared to one of said elements, and Wheatstone bridge apparatus controlled by 35 said movable elements and operatively connected with said auxiliary motor for starting and stopping the same.

5 5. In a mechanism for controlling movement at a distance, the combination with two or more movable elements normally moving in a predetermined relation and synchronized motors for moving the same, of means for correcting deviations from said predetermined relation comprising a differential connected 50 at one side to one of said motors, an auxiliary motor connected to the opposite side of said differential, connections between said differential and the corresponding said element, and Wheatstone bridge apparatus operatively connected with said auxiliary motor for starting and stopping the same.

6. In a mechanism for controlling movement at a distance, the combination with two or more movable elements normally moving in a predetermined relation and synchronized motors for moving the same, of means for correcting deviations from said predetermined relation comprising a differential connected at one side to one of said 65 motors, an auxiliary motor connected to the

opposite side of said differential, connections between said differential and the corresponding said element, and Wheatstone bridge apparatus controlled by said elements and operatively connected with said auxiliary motor for starting and stopping the same.

7. In a mechanism for controlling movement at a distance, a controlling element, one or more controlled elements, means whereby movement of the controlling element normally produces a corresponding movement of the controlled element or elements, and differential mechanism in the driving train of each controlled element and comprising an independently operated driving member actuated automatically upon the occurrence of any deviation of a controlled element from its normal relation to the controlling element for correcting said deviation.

8. In a mechanism for controlling movement at a distance, a controlling element, one or more controlled elements, centrally-controlled synchronized motors for moving said elements whereby movement of the controlling element is accompanied by a corresponding movement of the controlled element or elements, and differential mechanism in the driving train of each controlled element and comprising an independently operated driving member actuated automatically upon the occurrence of any deviation of a controlled element from its normal relation to the controlling element for correcting said deviation.

9. In a mechanism for controlling movement at a distance, a controlling element, one or more controlled elements, means whereby movement of the controlling element normally produces a corresponding movement of the controlled element or elements, and means for correcting any deviation of a controlled element from its normal relation to the controlling element comprising an auxiliary motor geared to each of the controlled elements and means for starting and stopping the corresponding auxiliary motor whenever a deviation from said normal relation respectively occurs and is corrected.

10. In a mechanism for controlling movement at a distance, a controlling element, one or more controlled elements, centrally-controlled synchronized motors for moving said elements whereby movement of the controlling element is accompanied by a corresponding movement of the controlled element or elements, and means for correcting any deviation of a controlled element from its normal relation to the controlling element comprising an auxiliary motor geared to each of the controlled elements and means for starting and stopping the corresponding auxiliary motor whenever a deviation from

said normal relation respectively occurs and is corrected.

11. In a mechanism for controlling movement at a distance, a controlling element, 5 one or more controlled elements, centrally-controlled synchronized motors for moving said elements whereby movement of the controlling element is accompanied by a corresponding movement of the controlled element or elements, a differential between each controlled element and its motor, an auxiliary motor connected to each differential, and means for starting and stopping the corresponding said auxiliary motor whenever 15 a controlled element respectively deviates from and returns to its normal relation to said controlling element.

12. In a mechanism for controlling movement at a distance, a controlling element, 20 one or more controlled elements, centrally-controlled synchronized motors for moving said elements whereby movement of the controlling element is accompanied by a corresponding movement of the controlled element or elements, a differential between each controlled element and its motor, an auxiliary motor connected to each differential, and means for starting and stopping the corresponding said auxiliary motor whenever 25 a controlled element respectively deviates from and returns to its normal relation to said controlling element comprising Wheatstone bridge apparatus operatively connected with said auxiliary motor.

13. In a mechanism for controlling movement at a distance, a controlling element, one or more controlled elements, centrally-controlled synchronized motors for moving said elements whereby movement of the controlling element is accompanied by a corresponding movement of the controlled element or elements, a differential between each controlled element and the motor, an auxiliary motor connected to each differential, and means for starting and stopping the corresponding said auxiliary motor whenever 45 a controlled element respectively deviates from and returns to its normal relation to said controlling element comprising Wheatstone bridge apparatus controlled by said elements and operatively connected with said auxiliary motor.

14. In a mechanism for controlling move-

ment at a distance, a controlling element, one or more controlled elements, centrally-controlled synchronized motors for moving said elements whereby movement of the controlling element is accompanied by a corresponding movement of the controlled element or elements, and means for correcting any deviation of a controlled element from its normal relation to the controlling element comprising an auxiliary motor geared to each of the controlled elements and electrical means for automatically starting and stopping the corresponding said auxiliary motor whenever a deviation from said normal relation respectively occurs and is corrected.

15. In a mechanism for controlling movement at a distance, a controlling element, one or more controlled elements, centrally-controlled synchronized motors for moving said elements whereby movement of the controlling element is accompanied by a corresponding movement of the controlled element or elements, and means for correcting any deviation of a controlled element from its normal relation to the controlling element comprising an auxiliary motor geared to 80 each of the controlled elements, and Wheatstone bridge apparatus operatively connected with said auxiliary motor.

16. In a mechanism for controlling movement at a distance, a controlling element, 85 one or more controlled elements, centrally-controlled synchronized motors for moving said elements whereby movement of the controlling element is accompanied by a corresponding movement of the controlled element or elements, and means for correcting any deviation of a controlled element from its normal relation to the controlling element comprising an auxiliary motor geared to 90 each of the controlled elements, and 95 Wheatstone bridge apparatus controlled by said elements and operatively connected with said auxiliary motor.

In testimony whereof I have signed this specification in the presence of two subscribing witnesses.

JEAN ALEXANDRE REY.
